UNITED STATES PATENT OFFICE.

JOHN L. BRINLY, OF LOUISVILLE, KENTUCKY, ASSIGNOR TO BRINLY-HARDY COMPANY, OF LOUISVILLE, KENTUCKY, A CORPORATION OF KENTUCKY.

PLOW-POINT.

No. 820,035.

Specification of Letters Patent.

Patented May 8, 1906.

Original application filed May 23, 1904, Serial No. 209,248. Divided and this application filed September 11, 1905. Serial No. 277,847.

To all whom it may concern:

Be it known that I, JOHN L. BRINLY, a citizen of the United States, residing at Louisville, in the county of Jefferson and State of Kentucky, have invented certain new and useful Improvements in Plow-Points, of which the following is a specification.

My invention relates to improvements in plow-points, and especially to improvements upon the plow-point shown and described in the patent to Thomas E. C. Brinly, No. 494,458, dated March 28, 1893, this application being a division of my pending application, Serial No. 209,248, filed May 23, 1904.

The general object of my invention is to provide an improved plow-point wherein the top rib is of material similar to that of the plate itself—that is, high-grade steel. By my improved article I am enabled to avoid the welding of a separate rib to the plate, and by avoiding this welding the article is strengthened and made materially stronger.

The specific object of my invention is to produce a plow-point which is more adapted to general hard use by its construction and one which saves a great amount of labor in the manufacture thereof. There is in this article a marked improvement in the wearing qualities over plow-points previously in use.

It has been found that great difficulty arises with plow-points previously in use where the rib is of different material from the plate to which it is welded in that the rib often becomes loose and the parts become disorganized. It is very essential that the side portion of the point, particularly that portion formed at the juncture of the rib and plate, be formed with a flat surface; but in forming the article from an integral plate by bending any portion thereof there is necessarily formed a curved surface at the point where the bend occurs. In my improved article I have strengthened the plate by a rib bent from the integral plate and have formed the edge of the plate with a flat surface at the point where the bending occurs.

My invention consists in the constructions and combinations of parts hereinafter described, and set forth in the claim.

In the accompanying drawings, which form a part of this specification, Figure 1 represents the blank from which the plate and top rib are formed. Fig. 2 is a perspective

view of the lip. Fig. 3 is a perspective view of the blank after the first bending operation. 55 Fig. 3^a is a section on the line *x* *x* of Fig. 3. Fig. 4 is a view after the second bending operation. Fig. 4^a is a section on the line *y* *y* of Fig. 4. Fig. 5 is a view of the piece after having been shaped up by the bulldozer, trip-hammer, or by hand. Fig. 5^a is a section on the line *z* *z* of Fig. 5. Fig. 6 is a perspective view of the completed point.

Like parts are represented by similar characters of reference in the several views. 65

In the said drawings, Fig. 1 shows the blank from which the point is formed, the said blank being of polygonal shape. The portion *a* is the plate of the finished product, *b* is the rib, and the portion *d*, projecting 70 from the base of the blank, forms the toe of the point. The blank shown in this figure is heated and bent along the dotted line by a process technically known as "bulldozing," although it can be done by various forms of 75 mechanism. The first bending step, as just explained, is so arranged that the blank will assume the shape shown in Fig. 3 and in section in Fig. 3^a. It will be observed that the portion *b* is bent past the center—that is, 80 through more than ninety degrees—and this feature is important by reason of the fact that the portion *b* must be bent upon the portion *a*, so that it will lie in a plane parallel with the portion *a*, and by reason of bending the 85 portion *b* past the center said portion *b* in the next step of the operation can be readily bent into the position shown in section in Fig. 4^a, while the portion *a* will be readily held against strains. Necessarily in operating upon plates 90 of high-grade steel there would be great difficulty in bending the portion *b* by two successive operations into the position shown in section in Fig. 4^a unless the plate was initially formed of the shape shown in Fig. 1 with the 95 portion *b* formed as shown therein, and then initially bending the portion *b* past the center, as heretofore explained. After the second bending operation the piece is dished, as shown in Fig. 5, and the rounded edge *b'* of 100 Figs. 4 and 4^a is flattened, as at *b*² in Figs. 5 and 5^a, and the square edge *b*³ of Figs. 4 and 4^a is beveled, as at *b*⁴, Fig. 5^a. The lip *c*, as indicated in dotted lines in Fig. 5 and also shown in Figs. 2 and 6, is then attached by 105 welding. The plow-point is completed by

adding the hole a' , as shown in Fig. 6, whereby the point is attached to the standard and by the end of the rib being drawn out and shaped, as at b^5 .

- 5 In use the parts are arranged as follows: The bent portion of the plate constituting the rib lies substantially in a plane parallel with the surface of the plate a and is called the "operating-surface" of the rib. This rib is 10 upon the upper side of the plow-point. The lip c is formed, as shown clearly in Fig. 2, and secured to the plate in the position indicated in Fig. 5, such that the lower surface of the lip comprises the bottom of the point, and the 15 extreme forward edge of the lip lies flush with the surface of the plate. It will be seen that by this construction the edges of the rib are all substantially flush with adjacent edges of the plate, and the plow-point rides 20 upon the bottom of the lip c , the article being shown in a novel arrangement of parts.

It will thus be seen that I am enabled to form from high-grade steel a plow-point in which the plate and the top rib are integral 25 without subjecting such high-grade steel to such a heat as would be necessary to make a

perfect weld of a separate plate and top rib, that the construction is economical, and that the plow-point by the use of the high-grade material thus permitted will possess great 30 strength and better wearing qualities than those heretofore produced.

Having thus described my invention, I claim—

As an article of manufacture, a plow-point 35 comprising a rib and plate formed integrally from a single piece, a portion of the operating-surface of the rib being above and substantially parallel with the surface of the plate, a lip formed from a separate piece secured to the plate below the rib portion and forming the bottom of the point, the sides of the lip and rib being substantially flush and together constituting the landside of the point, substantially as specified. 40

In testimony whereof I have hereunto set my hand this 7th day of September, A. D. 1905.

JOHN L. BRINLY.
